UNITED STATES PATENT OFFICE.

EDWARD P. VAN STONE, OF READING, MASSACHUSETTS, ASSIGNOR TO GENERAL ALLOYS COMPANY, OF BOSTON, MASSACHUSETTS, A CORPORATION OF MASSACHUSETTS.

RETORT.

Application filed April 7, 1927. Serial No. 181,718.

This invention relates to retorts for use in heating metal objects to be heat treated, and more particularly to retorts for this purpose which are arranged to be revolved during the 5 heating operation in order to heat the objects more uniformly.

Retorts of this general type usually have a substantially cylindrical body provided with a removable cover at one end through which 10 metal objects may be charged and discharged and at its other end with a neck. Heretofore, the substantially cylindrical body and neck have been formed as an integral hollow casting of bottle shape. Retorts of this type are 15 necessarily of large size and great difficulty has been experienced in their manufacture by casting. It is not uncommon in the manufacture of such castings to have three out of four rejected and discarded due to cracking 20 during the casting operation. Moreover, retorts cast in this manner readily become cracked during normal use on account of repeated heating and cooling which sets up tremendous strains in the casting.

25 It is an object of the present invention to provide a retort of this general type which is simple to manufacture and because of its construction is less susceptible to cracking during manufacture and use and which is 30 lighter in weight.

Before explaining the invention in detail, it is desired to point out that the embodiment of the invention described is merely by way of illustration and that the invention is in no 35 way intended to be limited thereby except as defined by the claims appended hereto.

The invention will be more clearly understood from the following description taken in conjunction with the accompanying drawings: in which,

Fig. 1 is an elevational view of a retort embodying the invention;

Fig. 2 is a sectional view taken upon the line 2—2 of Fig. 1;

Fig. 3 is a sectional view taken upon the line 3—3 of Fig. 1;

Fig. 4 is an end elevational view of the neck of the retort; and,

Fig. 5 is an end elevational view of the 50 neck end of the body of the retort.

In the drawings, a retort embodying the invention is illustrated and comprises a body portion 10, preferably of elongated cylindrical form, one end of which is provided with

a small annular shoulder 11 to provide a 55 gripping surface for a suitable clamp 12 for holding a cover 13 enclosing the end of the retort. The other end of the body portion is provided with a flange 14 extending therefrom and divided into a plurality of parts 60 by slots 15 preferably extending in a radial direction, each of said parts being re-enforced by one or more webs 16 extending to the body portion. A plurality of holes 18 are provided in the flange 14 for bolts 19 for securing the 65 neck 20 thereto.

The neck 20 is formed as a separate relatively small hollow casting which is tapered or flared outwardly to provide a surface engaging the flange 14 of the body portion and 70 is provided with a tongue 22 adapted for engagement with a groove 23 in the flange 14. The flared end portion of the neck 20 is reinforced by internal webs 24 and is provided with holes 25 to receive the bolts 19.

75 In accordance with the invention, distortion of the castings due to contraction is minimized. This is accomplished in the construction described by the provision of a plurality of slots 15 in the flange 14 which permits the various parts of the flange to move and partially or wholly close the slots 15 during contraction so that the flange is not subjected to the strains ordinarily encountered by the contraction of a large casting. The 80 various parts of the flange 14 and the flared end portion of the neck 20 are further reinforced by the webs 16 and 24 respectively. The engaging surfaces of the body portion 10 and neck 20 are provided with an inter-

fitting tongue and groove thereby providing a double seal tending to prevent the escape of gases from the interior of the retort. This 85 tongue and groove construction further assists in centering the parts during assembly. Preferably, the various parts are constructed with a substantially uniform thickness.

90 Heretofore, in retorts of this type in which the body portion and neck were cast integrally, it has been common practice to employ a relatively thick wall construction with the view of rendering the casting stronger and preventing too rapid cooling during the casting operation and thereby minimizing the tendency to crack. The retort construction of the invention is such that this 95 tendency to crack is materially reduced and it is possible to use a relatively thin wall con-

struction thereby bringing about an economy of materials and rendering the retort easier to heat with resulting fuel economy.

What I claim is:

- 5 1. In a retort, the combination of a large hollow body portion and a separate relatively small hollow neck secured together, said body portion having a slotted flange extending therefrom, said neck having an outwardly flared portion arranged to engage the flange on said body portion.
- 10 2. In a retort, the combination of a large hollow body portion and a separate relatively small hollow neck secured together, said body portion having a slotted flange extending therefrom, said neck having an outwardly flared portion arranged to engage the flange on said body portion, and webs re-enforcing the flange of the body portion and the flared portion of said neck.
- 15 3. In a large retort, the combination of a hollow body portion and a separate tapered hollow neck secured together with their engaging surfaces provided with a tongue and

groove, and means for minimizing distortion of said parts by contraction. 25

4. In a retort, the combination of a large hollow body portion and a separate relatively small hollow neck secured together, said body portion having a slotted flange extending therefrom, said neck having an outwardly flared portion arranged to engage said flange, and webs re-enforcing the flange of the body portion and the flared portion of said neck, 30 said flange and flared portion being provided with an interfitting tongue and groove. 35

5. In a retort, a body casting having an inwardly flanged open end, the flange being divided into a plurality of parts by slots, and an end casting secured to said flange. 40

6. In a retort, a casting comprising a large body portion and a flange extending therefrom divided into a plurality of parts by slots, said parts being re-enforced by webs extending to the body portion, and an end casting secured to said flange. 45

In testimony whereof I affix my signature.
EDWARD P. VAN STONE.
